PAPER CONTAINER

Lee D. Pierce, Fulton, N. Y.

Application September 29, 1934, Serial No. 746,251

17 Claims. (CL 229—4.5)

This invention relates to paper containers, particularly to containers of relatively large capacity, primarily intended for one-time use, usually for goods or products in bulk, and to containers of the so-called collapsible type, for shipment and storage in knocked-down or disassembled form, capable of setting up and assembly to operative form at the situation where the containers are to be loaded or charged with the goods or product to be shipped therein and dispensed therefrom, and by the term "paper", I include and mean any sheet-like material of the required strength, flexibility, durability, and other characteristics, necessary to render the container adaptable for the particular use for which intended, within the spirit and scope of my invention; and the objects and nature of the invention will be understood by those skilled in the art in the light of the following explanations of the accompanying drawings that illustrate what I now believe to be preferred mechanical expressions or embodiments of my invention from among other forms and arrangements within the spirit and scope thereof.

An object of the invention is to provide a shell or barrel adapted to be assembled with end closures, to provide a bulk container, with such shell collapsible to such form as to enable a multiplicity of like collapsed shells to be packed in compact space, for shipment or storage, by longitudinally nesting the collapsed shells one within the other with each collapsed shell, when removed from the nest, capable of easy expansion to cylindrical operative form into operative association with an appropriate end closure, and the opposite open end of the expanded cylindrical shell adapted to be closed by an appropriate end closure.

A further object of the invention is to provide tubular container shells capable of collapsing to longitudinally tapered or approximate conical form for packing by nesting, with such shells capable of easy expansion to approximate cylindrical operative form into operative association with container end closures.

A further object of the invention is to provide an improved collapsible tubular container shell with an exterior smooth surface of increased area for the reception of printing, and with an open end of increased stiffness or rigidity to receive the top cover, when said shell is expanded to approximately cylindrical form in operative association with an appropriate bottom closure.

A further object of the invention is to provide a tubular container shell of non-split or unbroken

tubular form capable of collapsing to form for packing and of expanding to operative approximately cylindrical form into operative association with an end stiffening closure, with the end in view of maintaining maximum rigidity and 5 stiffness of the mouth portion of the expanded shell against radial collapse or deformation, by the elimination of all longitudinal weakening, score or fold lines from the mouth end portion of the shell, except at a small fraction of the 10 circle thereof.

A further object of the invention is to provide a collapsible paper or substantially like material tubular shell adapted to be assembled with a separate restraining bottom cap to form a container with a bottom end sealing closure forming a permanent part of the shell and collapsible or expandable therewith, and characterized by its tissue or film-like thinness and preferable transparency, by being waterproof and inert to ice 20 cream and the ingredients thereof, and that will protect the container contents against contact with the bottom closing cap of the assembled container.

A further object of the invention is to provide 25 an assembled set up container that includes a paper or substantially like material tubular shell contractile or collapsible for packing and expansible to operative cylindrical form within a separate annularly-flanged surrounding restraining bottom cap to permanent holding operative association, wherein the shell is manufactured and delivered without the presence of exposed exterior adhesive for operative association with said cap, and wherein the bottom cap is manufactured and delivered with permanently adhering adhesive on the inner surface of its annular upstanding permanent flange for operatively uniting the bottom cap to the lower end of the shell forcibly expanded radially into contact with 40 the adhesive on said flange of the bottom cap completely around the circle thereof.

And a further object of the invention is to provide certain improvements in so-called collapsible containers with the ends in view of overcoming 45 certain difficulties and disadvantages in and incidental to the manufacture and use of collapsible containers now on the market, and to provide a highly desirable and advantageous container of this type.

With the foregoing and other objects in view, as will be developed by the description that follows, my invention consists in certain novel features, formations, arrangements and/or combinations, more fully hereinafter described and specified. 55

Referring to the accompanying drawings, forming part hereof:—

Fig. 1 shows in perspective the separated elements making up the assembled container illustrated by Fig. 2, the tubular shell appearing in Fig. 1 in operative expanded cylindrical form.

Fig. 2 shows in side elevation, an assembled set up container as an example of an embodiment of my invention.

Fig. 3 is a vertical section of the container of Fig. 2, partially broken away.

Fig. 4 is a perspective, more or less diagrammatically illustrating the tubular shell of the preceding drawing views (without the tissue-like end closure) in contracted form and the relatively small diameter bottom cap in which the shell is to be expanded.

Fig. 5 shows the parts of Fig. 4 with said shell partially expanded into operative association with said cap.

Fig. 6 shows the parts of Figs. 4 and 5 with the shell completely expanded in the cap to permanent operative association therewith to form the completed open-mouth container.

Figs. 7, 8 and 9 are more or less diagrammatical sections taken on the lines 7—7, Fig. 4; 8—8, Fig. 5; and 9—9, Fig. 6, respectively.

Fig. 10 shows a modified container in vertical section including the tubular shell of my invention operatively assembled with a modified form of bottom cap permanently united thereto in accordance with my invention.

Fig. 11 shows a container in vertical section, including the shell of the preceding views of the drawings expanded in and permanently secured to another modified form of bottom-closing cap.

Figs. 12 and 13 are side elevations of modified forms of my contractile collapsible tubular shell.

Figs. 14 and 15 are bottom end views of the shells of Figs. 12, 13, respectively, in contracted or collapsed condition.

Fig. 16 more or less diagrammatically shows in side elevation, a stack of the nested telescoped collapsed tubular shells of my invention.

In the examples illustrated to show various embodiments of my invention from among others, the tubular barrel or shell 1, is composed of a strong, stiff, yet resilient flexible wall that is uncut or unbroken throughout the circle of the tube and its operative length. This shell forms an unbroken or non-split tube, preferably cylindrical or of uniform cross sectional dimensions throughout its operative length when in expanded or operative form. The sheet material wall of this shell is comparatively heavy or thick where it is to be employed for a comparatively large size container for bulk products, such as bulk ice cream, and other bulk products, requiring containers of half-gallon, gallon, two and one-half gallon capacity, etc.

The cylindrical shell is usually composed of multiply sheet material, such as spirally wound, adhesively united, superimposed sheet ribbons, and is usually produced by tube winding machinery from sheet fibrous material such as suitable paper stock. However, I do not wish to limit my invention to spirally wound shells, however produced.

In the example shown, the tubular shell is square-cut at its ends, i. e., the ends of the shell are cut off in substantially parallel planes substantially perpendicular to the longitudinal axis of the shell.

With reference to Fig. 2, showing a complete closed bulk ice cream or other large-capacity con-

tainer, the shell 1, is capped at its bottom or lower end by any suitable bottom closure 2, and at its mouth or otherwise open upper end by any suitable cover or end closure 3. These end closures are preferably composed of fibrous material such as paper board or equivalent sheet material and are usually of the annularly flanged slip cover type of suitable stiffness and rigidity to serve to protect, stiffen and strengthen the shell and render the completed container of ample strength and rigidity against deformation to serve the purposes for which intended. The two end closures of a container are usually similar in formation and size, so that, in assembly, either end closure can be applied to either end of the shell, although I do not wish to so limit my invention. Each closure 2, 3, preferably includes a closed or imperforate end wall rigid with a laterally projecting, strong, substantially stiff or rigid unbroken cylindrical skirt or flange, 4, the internal diameter of which is approximately the same as or slightly less than the external diameter of the shell 1, when in expanded operative form. In the assembled condition, the end closures fit the shell end edges and the closure flanges 4, exteriorly and tightly surround the cylindrical outer surface of the shell ends.

The containers are stored and shipped to the user in knocked-down or separated condition, the end closures separated from the shells, and the shells collapsed for economy in the matters of space and freight rates. The containers are set up at the situation where they are to be charged or loaded with the bulk or other material or products for which intended. In assembling a container, the bottom closure 2 is placed on a suitable support with its flange 4 upstanding, the shell is then placed in a vertical upstanding position on the closure end wall within the flange 4, and the shell is then expanded radially to operative cylindrical form and into tight engagement with the inner surface of the flange 4, provision being made to operatively associate the shell and bottom closure in such manner that the shell and such bottom closure will not separate under the weight of the container contents. The container is then ready to receive its contents through the open upper end or mouth of the shell. After the container has been loaded, its mouth is tightly closed by application of the slip cover 3, or other suitable closure.

My invention is characterized by any suitable formation of the shell 1, whereby the shell can collapse or contract to a tubular form of relatively small cross-sectional dimensions at one shell end portion with respect to the cross-sectional dimensions of the opposite end portion, of the shell, to permit longitudinal nesting of a series of similar collapsed shells one into the other in succession, forming a stack of such collapsed, telescoped shells for economic storage and shipment, see Fig. 16. Each shell thus is capable of collapsing to a form for nesting, i. e., to a form wherein the shell longitudinally tapers or reduces in cross-sectional dimensions toward its bottom end, in such manner that a series of like collapsed shells with their relatively small ends foremost, can be successively telescoped longitudinally into the relatively large ends of the previously nested shells, to form a stack of telescoped or nested shells, wherein the shells are held together against normal backward longitudinal separation by the frictional engaging contact between the telescoped shells under the constant resilient tendency of each contracted

shell to expand laterally or radially to normal form within the shell in which telescoped and into snug frictional contact therewith.

The stacks of longitudinally nested collapsed shells can be, if so desired, packed and shipped in tubular containers.

Various cylindrical tubular shell formations are possible within my invention, to provide for shell collapse to longitudinally reducing or tapered form for packing or nesting and shell expansion to operative unbroken cylindrical form for operative association with a bottom closure and also, preferably, a top cover or closure. In the particular examples illustrated, the shell result sought is accomplished by providing the stiff resilient shell with a longitudinal infoldable panel or portion 6, of the shell wall extending throughout the length of the shell and preferably of progressively increasing transverse width from its relatively very narrow upper end 6a, at the mouth of the shell, to its relatively wide lower end 6b, at the shell bottom end. This longitudinal panel or portion 6 of the shell wall is in one piece or integral with the remainder of the shell wall, and is joined throughout its longitudinal margins into the remainder of the shell wall by transversely flexible imperforate hinge portions 7, each, preferably, continuous throughout the length of the shell. Thus, by exerting inward pressure by the hands or fingers on the said portion 6 of the expanded cylindrical shell, said portion 6 can be forced inwardly of the shell, on the hinge or bending lines 7, thereby circumferentially contracting the stiff resilient shell wall and reducing the cross-sectional dimensions of the shell, particularly if the fingers, when pressing said section or portion 6, inwardly, also press the same laterally within the interior of the thereby contracted tubular shell, see Figs. 4, 7, 14 and 16. The relatively great contraction of the bottom or lower portion of the shell and the relatively slight contraction of the mouth or upper end of the shell to produce the longitudinally tapered form of the contracted shell for nesting or packing purposes, and the increased stiffness of the mouth portion of the cylindrical expanded shell, result, in this example, from the upwardly reducing tapered or angular shape of the inwardly deformable portion or infolding hinged panel 6, of the shell wall.

This angular formation of the shell wall portion 6, is attained, in this example, by the divergence of the longitudinal hinge lines 7, from the mouth end of the shell to the bottom end of the shell to produce the gusset-like triangular longitudinal portion 6 of the shell wall. The downwardly diverging hinge lines 7 almost meet at the mouth end of the shell, as the purpose is to maintain the natural unbroken stiffness of the mouth end of the expanded cylindrical shell to the maximum by reducing the width of the upper end of portion 6, to the smallest possible fraction of the complete circle of said shell mouth, while attaining the desired shell contraction when collapsed. It is also desirable to reduce the width of the lower end of shell wall portion 6, to a minor fraction of the complete circle of the expanded cylindrical shell, so far as possible in attaining the desired contraction of the bottom end of the collapsed shell.

The hinge lines 7 are usually formed by compressing the paper wall of the shell between complementary straight line jaws of a high pressure press, one jaw within the cylindrical

tube and the other at the exterior thereof, both jaws fitting the wall throughout the length thereof. The pressure applied by these complementary jaws preferably compresses and breaks down the resiliency of the paper and bodily displaces the paper along each narrow line 7, to preferably form a groove at one face of the paper and a corresponding rib at the opposite face, and a consequently strong, yet pliable or transversely flexible bending line.

Each hinge can be formed by a single line 7, or to attain greater flexibility, a pair of slightly spaced lines 7a can be provided with a narrow non-compressed intervening hinge strip 7b, thereby forming a double hinge connection flexible inwardly and outwardly.

It is sometimes desirable to provide an intermediate bending or hinge line 7d, located about midway between the two diverging lines 7, 7, and approximately defining the longitudinal axis 20 of the infolding panel or portion 6, of the tubular shell. This line 7d permits the infolding panel 6, when pressed inwardly during the operation of collapsing the tubular shell, to fold or buckle inwardly on its longitudinal axis 7d, and assume 25 positions within the collapsed shell as shown by the drawings.

Figs. 13 and 15 show the herein described tubular shell 1 of my invention formed with the infolding panel 6 capable of buckling on its 30 longitudinal axis, all formed and provided by single depressed hinge lines 7, 7d.

Figs. 12 and 14 show the tubular shell 1 of my invention formed of the upwardly reducing infolding hinged panel 6, defined by a vertical 35 longitudinal single hinge or bending line 7, and a closely spaced pair of parallel lines 7a, angularly arranged with respect to line 7, and forming a double hinge, as hereinbefore described in connection with the shell formation shown by Figs. 40 1 and 2.

In all of these forms, when the shell is expanded to operative cylindrical form, the panel 6 is concavo-convex in cross section, forming a segment of the circle of the tubular housing, and 45 in fact, completing said circle.

During the operation of contracting the shell by swinging the panel 6 inwardly under the pressure of the fingers, the panel acts in effect as an inwardly breaking contracting toggle exerting 50 leverage on the remainder of the shell wall in drawing the same inwardly to bridge the gap left by the infolding panel 6, all against the resiliency or tension of the shell wall and the constant tendency thereof to spring outwardly to its original 55 diameter and form. Thus, when the contracted shell is inserted in the end cap 2, about as shown by Fig. 4, and allowed to expand under its own spring or resiliency, it will assume approximately the form shown by Fig. 5, although I do not wish 60 to so limit my invention.

When in the form of Figs. 5 and 8, the panel 6 forms an inwardly broken toggle. Outward pressure applied to the knuckle of this toggle, at point 7d, by the fingers or hand, will attain a 65 power multiplying leverage action on the shell in forcibly expanding the same to the complete circular form and pressing the same outwardly most tightly against the surrounding restraining flange 4, of the bottom cap, and in effect locking the toggle against inward collapse. The flange 4, is preferably very slightly less in internal diameter than the normal exterior diameter of the cylindrical lower end of the expanded shell.

If so desired, a slightly oversize inner paper 75

disk 9, can be forced down in the expanded cylindrical cell (Figs. 1, 3, 11) against the bottom cap 2, to lock the lower end of the cylindrical shell to and against the flange 4, of the cap, although I do not wish to limit my invention to the employment of such inner disk, see Figs. 6, 9, and 10.

It is essential in containers intended for assembly from collapsed or separated condition, at the situation where filled, that provision be made to operatively secure or join the shell and bottom caps, against separation under the weight of the load, when the loaded containers are lifted or transported. I have discovered that it is possible to so tightly associate the shell and bottom cap that the container will carry the load without shell and cap separation, even where the oversize inner locking disk 9 is not employed, where the inner surface of the flange 4, of bottom cap 2, carries an ample permanently adhering coating 10, of a strong tacky waterproof adhesive, preferably, previously applied thereto by the manufacturer of the container parts. The outer surface of the lower end of the shell 1, is manufactured and received by the user free of any adhesive. The manufacturer of the container parts, applies the coating 10, of strong tacky adhesive to and throughout the inner surface of the cap flange 4, and the container user thus receives the bottom caps. These flanges 4 are cylindrical and the caps are not capable of being nested, and the tacky adhesive on the inner surfaces of the cap flanges, does not come in contact with other parts or articles, but is protected therefrom by the flanges. The adhesive for this purpose is of great holding power or strength as an adhesive for paper and the like and has the capacity of remaining sufficiently tacky for the purposes of my invention, for a considerable length of time. If necessary to retain the necessary degree of tackiness for an indefinite period, the tacky inner surfaces of the caps can have inexpensive temporary coverings applied thereto.

Now, the particular required degree of adhesive strength gained in locking or securing the bottom caps to my shells, is due to the fact that my contracted shells are expanded within the relatively undersized cap flanges and are driven outwardly under pressure forcibly against the tacky surfaces, and thus held by the peculiar action of the panels 6, under the pressure of the hands or fingers, as hereinbefore described. Under this action, the bottom cap flanges and the lower ends of the shell become in effect permanently united.

Also, I have discovered that a liquid-tight bottom seal for containers of this assembled type can be attained by providing the lower end of my contractile shell with a film or tissue-like cover sheet 12, permanently secured to the shell 6 by the manufacturer and thus received by the user. This permanent bottom end cover 12, will, also, in the completely assembled and loaded container, in a measure relieve the bottom cap 2 of the weight of the container load, and thereby reduce the supporting means otherwise necessary to hold together the cover 2, and the shell 1.

The sheet 12 can be composed of flimsy tissue-like material of the necessary tensile strength, that is waterproof and inert to moisture and ice cream, and preferably transparent. Thin tissue-like or film-like sheet material having a cellulose ester base, or certain so-called "cellophane" sheets, or possibly certain modern high grade waterproof papers of high tensile strength are suitable for the purpose. The sheet 12 of large

size, is stretched smoothly across the lower end of the expanded cylindrical shell 1, and the surplus margin of the sheet is formed into a cylindrical skirt 13, by being pressed smoothly down around the outer cylindrical surface of the shell and permanently cemented thereto by a strong tacky adhesive, known to those skilled in the art for cementing sheet material having a cellulose ester base, such as common "cellophane". The surplus sheet material in the skirt is taken up by creases 10 and folds which are flattened out and pressed and cemented down.

The skirt 13, of the sheet 12, permanently surrounds the exterior of the lower end of the shell, and in the completed assembled container contacts and strongly adheres to the tacky adhesive coating 10, on the inner surface of the cap flange, 4.

This bottom sheet 12 is of such tissue-like flimsy material that it rumples up when the shell 20 to which it is permanently secured is collapsed and does not interfere with the contraction of the shell, or with the nesting of the shells provided therewith, nor does such sheet interfere with the expansion of the shell to cylindrical 25 form and operative association with the cap 2. When the shell is expanded to cylindrical form, the sheet 12, flattens out to drum form, and by reason of its great tensile strength does not fracture.

The peculiar contractile container shells of my invention can be employed with or without the bottom sheets 12 and with or without the applied adhesive on the inner surfaces of the cap flanges 4, and with or without the inner locking disks 9. 30

Various kinds of closure caps can be employed for the container ends. For instance, among others that can be employed, I show in Fig. 10, a strong drawn paper material ring 14, the up-standing annular portion of which forms the 40 flange 4, while the open center of the rigid drawn annulus 14 is closed by an imperforate disk 15, of paper or other suitable material set down within flange 4, and resting on the inturned annular ledge of the annulus. 45

In Fig. 11, I show a stiff rigid drawn or pressed paper cap, the imperforate bottom wall of which is formed with a surrounding annular cylindrical upstanding wall-forming flange 4.

The hinge lines joining the infoldable panel 6, into the unbroken annular wall of the tubular container body can be formed by depressed portions of the wall forming in effect grooves in one surface of the wall and complementary ribs at the opposite surface of the wall. While I show these ribs located at the inner surface of the wall of the body to facilitate the inward swing of the panel 6, yet the formation can be reversed with the ribs at the outer surface of the body, or at one longitudinal edge of panel 6, the ribs can be at the outer surface of the body while at the other longitudinal edge the ribs can be at the inner surface of the body. 55

The unbroken non-weakened formation of the 65 surrounding wall at the mouth or upper end of the expanded body, except at the very slight fraction of the circle of said end where the panel 6 terminates, gains certain important advantages. The strength of the stiff, comparatively thick re- 70 silient body wall of the expanded cylindrical body is thereby utilized against wall deformation and the operation of applying or removing very closely fitting or underside top slip covers, can be facilitated by slightly contracting the container 75

mouth by slightly inwardly flexing or infolding the upper end portion of panel 6.

In reference to that feature of my invention involving the bottom closure having the inner surface of its annular flange provided with a permanent adhesive coating characterized by its adhesive strength and capacity of remaining tacky for a long period of time, it will be noted that the body which has been expanded in the closure 10 tightly against the flange and its tacky coating, will be also held in the thus expanded form by the weight of the lading or content of the filled body.

What I claim is:—

1. A container shell of non-split tubular form having a stiff resilient annular wall provided with diverging longitudinal hinge lines forming said wall with a relatively-narrow infolding angular longitudinal panel.

2. A container shell of non-split tubular form, in combination with a separate annularly-flanged bottom closure cap adapted to be operatively assembled and associated with the bottom end of said shell against separation therefrom under the weight of the load in the shell, the annular wall of said shell including an infolding longitudinal panel, decreasing in width from the bottom end of the shell to the top end of the shell, and adapted to be forced inwardly of the shell to contract the same to collapsed form for nesting before said shell has been associated with said cap, said shell adapted to be expanded to operative cylindrical form with its bottom end located in said cap.

3. A container shell of tubular form having a stiff resilient imperforate non-split surrounding wall provided with longitudinal diverging hinge lines forming an infoldable panel, the maximum width of which constitutes but a minor fraction 40 of the circle of the cylindrical shell, said shell capable of being contracted to collapsed form for nesting by forcing said panel inwardly of said shell, said shell adapted to be expanded to operative cylindrical form by application of outward pressure on said infolded panel, said panel joined in said wall to provide a lever toggle action in expanding and contracting the shell.

4. A stiff, resilient container shell of non-split tubular form, said shell having an infoldable panel included in the surrounding shell wall and reducing in width longitudinally of said wall from the bottom end thereof toward the top end, said panel outlined by longitudinal hinge lines pressed in said wall, the maximum width of said panel occupying but a minor fraction of the wall circle, said shell adapted for contraction to collapsed form for nesting by inwardly pressing and buckling said panel, the collapsed shell adapted to be expanded to operative cylindrical form for operative association with a bottom closure cap.

5. A tubular container shell of stiff resilient material, that is substantially cylindrical when in operative expanded form, said shell being permanently creased from end to end at a relatively narrow portion only to provide a longitudinally reducing infolding wall portion adapted to be forced inwardly from the approximate circle of the shell to thereby contract the shell to temporarily tapered form for nesting purposes, said wall portion adapted to be forced outwardly to expand and restore said collapsed shell to its operative substantially cylindrical form with said portion completing the circle thereof.

6. A tubular container shell of normal substantially-cylindrical form, said shell substantially

throughout its length and at one side portion only, having a relatively-narrow transversely-arcuate longitudinal infolding portion of minimum width at the upper end of the shell, and adapted to be forced inwardly from the circle of the cylindrical shell to contract said shell to temporarily collapsed form and to be forced outwardly to expand and restore the collapsed shell to cylindrical form, said portion occupying but a minor fraction of the circle of the expanded cylindrical shell.

7. A tubular container shell of substantially-cylindrical normal form, having a permanently creased relatively-narrow longitudinal portion extending to the mouth of the shell and of maximum width at the bottom end of the shell, and adapted to be forced inwardly from the circle of the expanded cylindrical shell, to thereby contract the shell to collapsed form for packing, and to be forced transversely outwardly of the collapsed shell to expand and restore the same to normal operative cylindrical form.

8. A tubular container shell of substantially stiff resilient material having in one side portion only, a narrow longitudinal infolding portion integral therewith and extending from end to end of the shell and of minimum width at the mouth end of the shell, the mouth end of the expanded shell being stiff and resilient throughout the annulus thereof to resist radial distortion and infolding except at the point therein where said portion terminates, said shell adapted to be temporarily contracted under tension to tapered form by movement of said portion inwardly, and to be restored to operative expanded form by movement of said portion outwardly.

9. A tubular container shell of substantially stiff resilient material, having a mouth end and a bottom end; and a closure adapted to be assembled with said shell to close said bottom end; 40 said shell being provided at one side thereof only with adjacent permanent preformed non-parallel bending lines extending longitudinally of the shell and approximately meeting at the mouth end of the shell and relatively widely spaced at the bottom end of the shell, and adapting the shell for contraction to collapsed form for nesting purposes, and for expansion from collapsed form to expanded cylindrical form with its bottom end extending into and expanding to tight fit within said closure.

10. A tubular container shell having a longitudinally-extending infolding portion of maximum width at one end of the shell and of minimum width at the other end of the shell, where- 55 by the shell can be contracted for nesting, and expanded to operative form, in combination with an annularly flanged bottom closure, the bottom end of said contracted shell adapted to be expanded to operative form within and tightly fitting said closure.

11. A tubular container shell preformed for expansion from collapsed form to operative expanded form; in combination with an annularly-skirted closure provided on the inner surface of its skirt with previously-applied substantially-permanently-tacky adhesive, an end of said collapsed shell adapted to be expanded forcibly to operative form within said closure into tight operative holding engagement with the tacky adhesive-carrying inner surface of the closure skirt.

12. A tubular container shell provided with preformed bending lines rendering the shell approximately radially contractile for nesting purposes, and expansible to operative expanded

- form; in combination with an annularly-skirted end closure cap provided on the inner surface of its annular skirt with waterproof adhesive characterized by its substantially-permanent tacky nature, the bottom end of said collapsed shell adapted to be radially expanded to operative form within said closure and forcibly into tight operative holding engagement with the tacky adhesive-carrying inner surface of the closure skirt.
- 10 13. A tubular container shell of stiff resilient material having a longitudinal infolding portion of maximum width at one end of the shell, whereby the shell can be contracted to collapsed form for nesting, by relative substantially-radial inward movement of said portion, and can be expanded to operative form by outward movement of said portion, and a thin flexible pliable sheet of water and grease resistant material of substantial tensile strength extending transversely across said end of the shell and covering the opening thereof and around its edges permanently secured to the surrounding margin of said shell, whereby said sheet collapses when the shell is contracted, and stretches and flattens out when said shell is expanded to operative form.
- 15 14. A tubular container shell of stiff resilient material throughout its length permanently creased to provide a relatively-narrow longitudinally-reducing infolding portion of maximum width at one end of the shell, whereby said shell can be temporarily contracted to tapered collapsed form for nesting purposes by forcing said portion inwardly to flex the shell under tension
- 20
- 25
- 30

to return to its normal circular form, and can be expanded from collapsed form to operative form by relative substantially-radial outward movement of said infolded portion, in combination with an annularly skirted closure in which said collapsed shell end is adapted to be expanded to operative end closing association.

15 15. A tubular expansible and contractile container shell of substantially stiff resilient material having a relatively narrow infolding portion 10 extending from end to end of the shell and defined by permanent non-parallel bending lines.

16 16. A tubular cylindrical container shell of substantially stiff resilient non-metallic material having longitudinal non-parallel bending 15 lines substantially meeting at one end of the shell and spaced their maximum distance apart at the opposite end of said shell and defining a relatively narrow infolding portion of the shell, whereby said shell can be contracted for nesting 20 purposes and expanded to operative form.

17 17. A substantially-cylindrical tubular container shell of substantially stiff resilient material having cooperating longitudinal bending lines substantially meeting at one end of the shell 25 and relatively widely spaced at the other end of the shell and defining a longitudinal infolding portion of said shell, whereby said shell can be contracted for nesting purposes and expanded to operative cylindrical form, said portion provided with a bending line intermediate its width and substantially throughout its length.

LEE D. PIERCE.
